No. 14,555 JAN 22, 1884

UNITED STATES PATENT OFFICE.

JAMES DWYER, OF DETROIT, MICHIGAN, ASSIGNOR TO THE PENINSULAR STOVE COMPANY, OF SAME PLACE.

DESIGN FOR A STOVE.

SPECIFICATION forming part of Design No. 14,555, dated January 22, 1884.

Application filed October 1, 1883. Term of patent 7 years.

To all whom it may concern:

Be it known that I, JAMES DWYER, of Detroit, in the county of Wayne and State of Michigan, have invented a new and original 5 Design for Stoves, of which the following is a specification.

The leading features of my design consist in a rectangular base-burning stove consisting of a base and four sections, each section projecting forward beyond the next higher one, and separated therefrom by a projecting molding, and in the ornamental figure at the top of the stove.

Referring to the accompanying photograph, 15 A represents the base of the stove, made of cast-iron, ornamented with raised figures.

B represents the lower section or ash-pit, in which is a damper, and in front of which is a nickel-plated foot-rest.

20 C represents the section which surrounds the fire, and contains on the front and sides a double row of windows separated by an ornamental molding, the lower windows having a single row, and the upper windows having 25 a double row, of panes, showing the lower part of the magazine.

D represents a section above C, having its front beveled or rounded toward the rear of

the stove, and having on its front and sides nickel-plated panels, having raised ornaments 30 of flowers and vines thereon.

E represents the top section, having on its front and sides sunken panels, in which are set encaustic tiles.

F represents a figure on the top of the swing- 35 ing magazine-cover, consisting of a kneeling cupid holding a hammer raised in one hand, as in the act of striking an anvil which stands in front of him.

I claim—

1. The design for a stove, herein set forth and represented.

2. A design for a base-burning stove, consisting of the base and four sections shown, each section projecting beyond the next higher 45 one, and the two upper sections having on their fronts and sides the ornamental panels described.

3. The design for a stove shown, having on its top a figure of a cupid kneeling in front of 50 an anvil, with one hand raised and holding a hammer.

JAMES DWYER.
